UNITED STATES PATENT OFFICE.

JAMES DOCKSTADER, OF SYRACUSE, NEW YORK.

CUE-RACK.

SPECIFICATION forming part of Letters Patent No. 615,821, dated December 13, 1898.

Application filed April 30, 1898. Serial No. 679,305. (No model.)

To all whom it may concern:

Be it known that I, JAMES DOCKSTADER, a citizen of the United States, and a resident of Syracuse, in the county of Onondaga, in the State of New York, have invented new and useful Improvements in Cue-Racks, of which the following, taken in connection with the accompanying drawings, is a full, clear, and exact description.

10 This invention relates to the class of cue-racks which are provided with means for locking the cues in the rack.

15 The object of the invention is to provide a cue-rack which shall be simple, compact, and inexpensive in construction and more convenient and efficient in locking and unlocking the cues in the rack; and to that end the invention consists, essentially, in a cue-rack provided on its upper portion with a stop limiting the vertical movement of the cue, a vertically-movable prop in the lower portion of the rack lifting the cue to the aforesaid stop, a lock retaining said prop in its elevated position, and a guard preventing lateral movement of the cue upon the prop; and the invention also consists in certain novel features 25 of the detail construction of the cue-rack, as hereinafter described and claimed.

20 In the accompanying drawings, Figure 1 is a front view of a cue-rack embodying my invention. Fig. 2 is a vertical transverse section on line X X in Fig. 1, and Fig. 3 is an enlarged vertical longitudinal section of a portion of the case containing the locks for retaining the cue-supporting props in their elevated positions.

25 A represents the rack-frame, which may be of any desired design. The base of this frame is formed with a case b, extending across said frame, the interior of which case is provided with vertical guides c c, and the top of the case is provided with apertures d d adjacent to the aforesaid guides. On these guides slide props e e, which protrude through the apertures d d and have affixed to their protruding upper ends cue-seats f f, which are provided with upward-projecting cue-retaining guards f' f', as more clearly shown in Fig. 3 of the drawings.

30 Each of the aforesaid props is provided on its side with a vertical ratchet t, preferably formed directly on the props, said ratchets

having the horizontal or abrupt portions of their teeth facing downward, for the purpose hereinafter explained. Adjacent to each of 55 said ratchets is a suitable lock g, secured in the case b and having its bolt g' shaped to enter between the ratchet-teeth and by engaging the horizontal or abrupt portion of the tooth directly over the bolt lock the prop, so 60 as to retain it in its elevated position. Each lock is provided with a special key h to insure private use of the cue seated upon the prop e controlled by the lock.

65 The top portion of the frame A has attached to it a cue-guide a, consisting of a horizontal transverse board in which are a series of holes through which the upper ends of the cues l l pass and are thus guided and supported in vertical position. Over said guide 70 is a stop o, consisting of a board disposed parallel with the board a and secured to the frame A.

75 The manner of using the described cue-rack is as follows: The cue is locked in the rack by the prop e supporting said cue and pushed up to cause the upper end of the cue to abut against the under side of the stop o, in which position the prop is retained by the bolt of the lock g engaging the ratchet t. The guard 80 f', surrounding the cue-seat f on the prop, prevents the cue from being drawn out laterally from said seat. When it is desired to remove the cue from the rack, it is only necessary to introduce the key h into the lock 85 and turn the key to withdraw the bolt g' from the ratchet t. The prop, with the cue seated thereon, then drops and allows the cue to be lifted from the seat f and drawn out laterally over the guard f'. In replacing the cue in 90 the rack the cue is simply inserted in the upper guide a and placed upon the seat f, and then the prop is pushed up until the upper end of the cue comes in contact with the stop o, and in this position the cue is locked by 95 the bolt of the lock engaging the ratchet and retaining the prop in its elevated position.

What I claim is—

1. A cue-rack provided on its upper portion with a stop limiting the vertical movement of the cue, a vertically-movable prop in the lower portion of the rack lifting the cue to the aforesaid stop, a lock retaining the prop in its elevated position and a guard prevent-

ing lateral movement of the cue upon the prop as set forth.

2. The combination of the rack-frame formed with a case across its base, vertical guides in said case, props sliding on said guides and protruding through the top of the case, ratchets on the sides of the props, locks in the case engaging the ratchets and confining the props in their elevated position, cue-
seats on the upper ends of the props and

formed with cue-retaining guards surrounding the seats, cue-guides in the top portion of the frame, and a stop over said guides receiving the impact of the cues lifted by the props as set forth.

JAMES DOCKSTADER.
